UNITED STATES PATENT OFFICE.

HENRY S. BREWINGTON, OF BALTIMORE, MARYLAND.

WRITING-PEN.

1,089,041.

Specification of Letters Patent.

Patented Mar. 3, 1914.

Application filed March 25, 1913. Serial No. 756,669.

To all whom it may concern:

Be it known that I, HENRY S. BREWINGTON, a citizen of the United States, residing in Baltimore city and State of Maryland, have invented certain new and useful Improvements in Writing-Pens, of which the following is a specification.

My invention relates to an improvement in writing pens, the object being to provide 10 a pen which will write a maximum number of letters without redipping the pen in the ink, having to a limited degree the qualities of a fountain pen, while at the same time it is a pen which may be used with an ordinary pen holder.

With the foregoing object in view, my invention consists in a pen made from a single piece of sheet metal, having one or more corrugated or fluted wings, the wings being 20 bent beneath the body part of the pen to form a plurality of channels, which channels are formed by the corrugations, for retaining a quantity of ink, the channels being open are thus rendered accessible for the 25 purpose of cleaning the pen. The lower ends of the wings being formed that when the wings are bent beneath the body part, the ends of the wings extend down well under the nibs of the pen for the purpose 30 of feeding the ink to the point, so that all combine to hold the ink and pay it out as required in the operation of writing.

My invention further consists, in certain novel features of construction and combinations of parts which will be hereinafter described and pointed out in the claims.

In the accompanying drawings forming a part of this specification, in which like characters are used to designate like parts 40 in the several views shown; Figure 1 is a view of the blank; Fig. 2 is a view of the blank after the corrugations have been formed therein; Fig. 3 is an elevation of the completed pen; Fig. 4 is a longitudinal 45 sectional view of the pen, and Fig. 5 is a transverse section on the line 5—5 of Fig. 3.

A, represents the body part of the pen, having the usual concavity 1 throughout its length, it being preferably rounded at one 50 end where it enters the pen holder, and pointed at the other end 2, it may be of various shapes. The pointed end 2 has the usual slit 3, and orifice 4 whereby the pen is divided into nibs 5—5. At the sides the two

wings 6—6 are formed, preferably as an integral part, and the forward ends of the wings are sharp and pointed at 7—7, and extend well down toward the point of the pen. The wings relative to the body part are longitudinally corrugated or fluted at 8 to 60 form the channels 9.

In the manufacture of the pen, the body part is preferably stamped by a suitable die (not shown) from a sheet of metal, the blank thus stamped being shown in Fig. 1. 65 The wings 6—6 are then corrugated as indicated at 8 in Fig. 2, forming the channels 9, the wings are then bent beneath the body part, completing the pen as shown in Fig. 3. The points 7—7 extend well down toward the point 2, under the nibs 5—5 in order to supply the ink evenly to the point of the pen. In this way a pen is formed 70 which carries a large supply of ink in the channels 9, which ink is made to flow gradually along the nibs to the point 2 of the pen as it is required in writing. Each channel, 75 as well as the recesses 10 between the corrugations and the body part, and the orifice 4 contribute to hold the ink and to supply it 80 as it is required.

The construction of the pen is such that the channels are easily accessible for the purpose of being cleaned, whereby the life and usefulness of the pen is prolonged to a 85 greater degree and advantage, as compared with pens of different structure having the same object in view.

Various other modifications might be resorted to without departing from the spirit 90 and scope of my invention, and hence I do not wish to limit myself to the exact construction as herein set forth, but:

Having fully described my invention, what I claim as new and desire to secure by 95 Letters Patent, is:—

1. A pen of the character described, having integral corrugated side wings forming open channels therein, which wings are bent beneath the body part of the pen. 100

2. A pen of the character described, comprising a body part having integral side wings, the wings being longitudinally corrugated relative to the body part forming longitudinal open channels therein, which 105 wings are bent beneath the body part of the pen.

3. A pen of the character described, made

from a single piece of sheet metal, comprising a body part having integral side wings pointed on their lower ends, the wings being longitudinally corrugated relative to the said body part, forming longitudinal open channels therein, which wings are bent beneath the body part of the pen with the pointed ends of the said wings extended

downwardly toward the point and under the said body part of the pen.

In testimony whereof I affix my signature in presence of two witnesses.

HENRY S. BREWINGTON.
